CLAIM

The ornamental design for a vegetable and/or fruit holder for facilitating peeling thereof, as shown and described.

DESCRIPTION

FIG. 1 is a perspective view of a vegetable and/or fruit holder for facilitating peeling thereof showing our new design;

FIG. 2 is a side elevational view thereof;

FIG. 3 is an elevational view of the opposite side;

FIG. 4 is a front elevational view thereof;

FIG. 5 is a rear elevational view thereof;

FIG. 6 is a top plan view thereof;

FIG. 7 is a bottom plan view thereof;

FIG. 8 is an exploded perspective view showing the components of our design in disassembled relation;

FIG. 9 is a fragmented side elevational view showing the upper portion of our design with the ring member mounted so as to assume its uppermost position;

FIG. 10 is a fragmented side elevational view showing the upper portion of our design with the ring member mounted so as to assume its lowermost position;

FIG. 11 is a perspective view showing our design being held in position above a vegetable;

FIG. 12 is a perspective view showing our design being held in one hand with the prongs forced into a vegetable, and with a peeler being held in the operator's other hand;

FIG. 13 is a perspective view showing our design after the peeling operation has been completed; and,

FIG. 14 is a perspective view showing our design after the internal plunger thereof has been forced downwardly to dislodge the peeled vegetable from the prongs.

The portions shown in broken lines in FIGS. 11—14 are for illustrative purposes only and form no part of the claimed design.
